UNITED STATES PATENT OFFICE.

ALEXANDER L. MUNRO, OF MILWAUKEE, WISCONSIN, ASSIGNEE TO SMITH ENGINEERING WORKS, OF MILWAUKEE, WISCONSIN, A CORPORATION OF WISCONSIN.

SAND-SETTLING TANK.

Application filed November 17, 1921. Serial No. 515,925.

To all whom it may concern:

Be it known that I, ALEXANDER L. MUNRO, a subject of the King of England, and resident of Milwaukee, in the county of Milwaukee and State of Wisconsin, have invented new and useful Improvements in Sand-Settling Tanks, of which the following is a description, reference being had to the accompanying drawings, which are a part 10 of this specification.

This invention relates to classifying or dewatering sand settling tanks of the tilting type wherein an accumulation of sand is relied on to overbalance the tank and 15 cause it to tilt and thereby open the discharge valve.

A particular object of the invention is to accommodate an uninterrupted flow of material, permitting the clear water to over- 20 flow after having been deflected to induce a deposit of sand at a point where it will contribute to the overbalancing influence for opening the discharge valve.

Another object of the invention is to 25 utilize such deflector as a means for locating the surplus material where it will contribute to the overbalancing influence for opening the discharge valve at times when the tank has a tendency to become chocked.

With the above and other objects in view, 30 the invention consists in the sand-settling tank as herein claimed, and all equivalents.

Referring to the accompanying drawings, in which like characters of reference indicate 35 the same parts in different views,

Figure 1 is a central sectional view of a sand settling tank constructed in accordance with this invention;

Figure 2 is a plan view thereof, and

Figure 3 is an end view with the counterweight removed.

In these drawings 10 indicates the settling tank proper, which may, for convenience, be of a hopper shape and preferably, as shown, 45 with one end wall vertical and the opposite wall inclined to direct material toward the vertical wall, and the side walls converging to a discharge opening 11. This tank is pivotally supported on a frame 12 by means of knife edge trunnions 13 on the opposite sides rocking in suitable bearings 14. The trunnions are located considerably back of the center of the tank so that the vertical wall end of the tank overweighs the other. 50 This end of the tank is therefore counterbal-

anced by means of a weight 15 on a lever 16 fulcrumed at 17 on the frame and having a stirrup or link 18 connecting its shorter end with a hook 19 on the vertical wall of the tank. 60

A bell crank lever 20 pivotally mounted on the vertical wall of the tank carries a rubber-faced valve 21 to close the discharge opening 11 of the tank and this lever is connected by means of a connecting rod 22 with the lever 16 in such a manner that the movement of lever 16 to lift the weight 15 serves to withdraw the valve from its seat to permit a partial discharge of the contents of the tank through the discharge opening. 70 A stop 22' is provided to limit the movement of the bell crank and, by its adjustment, determine the degree of opening of the valve 21.

Preferably a vertical partition 23 extends 75 across the tank in the neighborhood of the trunnions and some distance above the inclined end wall to form a baffle or deflector normally requiring the material to pass beneath it as such material travels through the tank from the vertical end wall thereof toward the inclined end wall. Material may be delivered to the larger end of the tank by a trough 24 or other suitable means and, after passing beneath the partition 23 and 80 after depositing the heavier solids in the bottom of the tank, it flows out through a discharge spout 25 at the upper end of the inclined end wall. As the sand and heavier solids which settle in the bottom of the tank 85 are caused by the formation of the tank to gather at the larger end thereof, this end will gradually become heavier until the counter-weight can no longer balance it, when the tank will swing on its pivotal 90 mounting and slightly lift the counter-weight. This movement of the counter-weight and tank causes the connecting rod 22 to pull on the bell crank 20 and open the valve 21, permitting the sand in a comparatively dewatered state to discharge through the discharge opening 11. When enough of the sand has been discharged in this manner to restore equilibrium the counter-weight again returns the tank to its normal position, closing the valve or partly closing it, so that the accumulated sand is discharged intermittently or, under favorable conditions, continuously at the rate it is being fed to the tank. 100

The deflector prevents the sand and other solids in suspension from being carried by the current of water directly to the discharge spout, requiring it instead to duck beneath it, thus facilitating its separation and deposit. Should the mound of sand build up beneath the partition without causing the operation of the discharge valve, the restriction to the flow beneath the partition would cause the material to back up behind the partition and so add its weight to the larger end of the tank to aid in overcoming the balance weight, thus opening the valve and relieving the congested condition. As the downward movement of the tank moves the discharge opening away from the valve as well as moving the valve away from the opening, it is evident that the control is very sensitive.

By this means water-carried sand may be classified or dewatered with a continuous operation with automatic control.

What I claim as new and desire to secure by Letters Patent is:

1. In combination, a tank pivotally supported nearer one end than the other, a partition across the tank near the pivotal support with its upper edge below the edge of the tank to permit material to flow over it, a suitably fulcrumed counter-weight lever having connection with the larger end of the tank, a valve mounted on the tank for closing a discharge opening at the bottom of the tank, and a connecting rod connecting the valve with the counter-weight lever.

2. In combination, a hopper-shaped tank having a discharge opening at its bottom and pivotally supported nearer one end than the other, a partition across the tank with space between its lower edge and the bottom of the tank adapted to be closed by sand and with its upper edge lower than the upper edge of the tank but higher than the discharge opening, a suitably fulcrumed counter-weight having connection with the larger end of the tank, a bell crank lever fulcrumed on the tank, a valve carried thereby for closing the discharge opening, and a

link connecting the bell crank lever with the counter-weight lever.

3. In combination, a tank having an inclined bottom with a discharge opening at the lowest point thereof, trunnions on the sides of the tank on which the tank is pivotally mounted, a partition extending across the tank and spaced from the inclined bottom and having its upper edge lower than the upper edge of the tank but higher than the discharge opening to raise the level of the contents of the tank at one end thereof, and a valve for closing the discharge opening operated by the pivotal movements of the tank.

4. In combination, a tank having an inclined bottom with a discharge opening at its lower end and an overflow spout at its upper end, trunnions on the sides of the tank on which it is pivotally mounted, a partition extending across the tank and spaced from the inclined bottom, a hook on the deeper end of the tank, a suitably fulcrumed counter-weight lever, a link connecting the counter-weight lever with the hook, a bell crank lever fulcrumed on the tank, a valve carried thereby for closing the discharge opening, an adjustable stop for limiting the movement of the bell crank lever, and a link connecting the counter-weight lever with the bell crank lever.

5. In combination, a hopper-shaped tank with pivotal supports, having a discharge opening at or near its bottom, a valve connected to and operated by said tank for opening and closing said discharge opening, a wall in said tank dividing same into two compartments connected by a passage below said wall, said wall being so placed that the accumulation of sand will gradually close the passage between the said compartments, whereby the increase in the volume of water in the first compartment, in combination with the accumulated sand, will cause the tank to tilt and discharge a portion of its contents.

In testimony whereof I affix my signature.
ALEXANDER L. MUNRO.
